UNITED STATES PATENT OFFICE.

ROBERT ALEXANDER STEPS, OF LOS ANGELES, CALIFORNIA.

SCREEN PIPE.

Original application filed March 30, 1923, Serial No. 628,945. Divided and this application filed September 30, 1925. Serial No. 59,585.

My present invention relates to an improved modification of the more general invention shown in my Patents Nos. 1,207,808 and 1,207,809, and this present application is a division of my co-pending application Serial Number 628,945, filed March 30th, 1923, the latter covering the method hereinafter disclosed.

The object of the present invention is to produce screen pipes such as are used in oil wells, water wells, etc., and to make such pipes with the combined benefits of increased screening capacity, increased strength, and reduced production costs.

It is understood that the screen pipes to which this invention applies is used in oil or water wells for the purpose of holding the sand and gravel out, while the fluid passes through and is pumped to the surface of the earth by proper pumps installed in the well. If the natural pressure on the fluid is sufficiently great the pump may of course be dispensed with as the fluid will then rise in the well under its own pressure.

Screen pipes of this sort are made of heavy steel or iron pipe with suitable screening apertures formed therein. The pipe comes in sections of various lengths, often about 20 ft. each, and from 4 to 16 inches in diameter, and these sections are screwed together to give the required length of screen corresponding with the thickness of the strata in which the desired fluid is found.

The tendency of course is for the sand and gravel to come through the screen with the fluid, but this is undesirable for many reasons, and on this account care must be exercised in so forming the screening apertures that they hold back the sand effectively without retarding the flow of the liquid.

It is this result which my invention accomplishes very nicely. The screening apertures formed in accordance with my invention are narrower on the outside of the pipe than they are on the inside, so that the external sands are held out right at the outside surface of the pipe, but if any particles get past the narrow outside portion of the slot they pass right through the slot without sticking or clogging therein, as the slots which I produce are wider toward the inside than they are toward the outside of the pipe where the real excluding action of the same is effected.

For the purpose of increasing the screen-

ing capacity without increasing the cost of manufacture of this kind of screen I have grouped my slots into pairs, because by my new method of operation I am now able to produce a pair of slots as easily as a single slot could be produced, so that the added screening benefit of the extra slot is obtained without any increase in cost.

In the accompanying drawings Fig. 1 shows a way of carrying out the first step in my invention, which consists in forming pairs of slots in the pipe, preferably by a pair of slotting saws mounted on a common arbor. Fig. 2 is a side view indicating the shape of the slotting saws diagrammatically. Fig. 3 shows a way of carrying out the second step in my invention whereby the slots are formed so as to be narrower toward the outside of the pipe than they are at the inside of the pipe. Fig. 4 is a side view of the tool shown in Fig. 3. Fig. 5 shows another way of carrying out the second step of my invention, and Fig. 6 is a side view of the tool shown in Fig. 5. Fig. 7 shows a short piece of the screen pipe finished in accordance with my invention, and Fig. 8 is a transverse section of same.

By mounting the usual slotting saws close together on the common arbor 2, Fig. 1, a pair of slots 3 may be cut in the wall of the pipe 4, a bar 5 separating the slots in the pair. At the end of this first step in my method the side walls of the slots are substantially parallel, and the slots are as wide on the outside of the pipe as they are on the inside of the pipe. Figs. 3 and 4 show a roller 6 adapted to bridge across the pair of slots, the edges 7 of the roller being spaced sufficiently apart to rest on the edges of the slots which are furthermost from each other. By any suitable means, this roller may be pressed down on the pipe at the same time that it is rolled back and forth along the length of the slots, and as this continues these edges of the slots are pressed toward each other.

In practice I use a pneumatic or hydraulic cylinder for producing the required pressure on the roll, and in view of the concavity of the roll the above operation is very nicely accomplished. In fact, the number of strokes back and forth along the slots, determines the degree to which the lips are pressed toward each other, and if narrower slots are desired it is merely necessary to

give the roller a few more strokes before the pressure is released.

At the end of this rolling operation the slots are seen to be narrower at the outside of the pipe than they are at the inside.

This gives the effective screening qualities which have already been described.

Figs. 5 and 6 show another tool 11 in the nature of a chisel, which may be used in place of roller 6. In this case the chisel may be struck with any sort of a hammer on the chisel head 12 and the opposite edges of the slot will thus be forced or pressed toward each other.

15 After completing one pair of slots the operation is repeated as often as desired until the entire section of pipe is thus perforated. It is obviously important that the slots in each pair should be comparatively close together compared with the distance between neighboring pairs of slots, as this gives the increased screening area without correspondingly weakening the pipe. Also in the longitudinal spacing of the slots as shown in Figs. 7 and 8, where the length of the slot is disposed substantially parallel to the axis of the pipe, the screen is very strong in tensile strength because the transverse section of the pipe has been impaired to a minimum, and the screen also is very strong against external compression strains because the grouping of the slots in pairs leaves the pipe with much larger uncut arches between the slots than when the individual slots are 30 equally spaced circumferentially around the pipe. Besides the screen pipe can be manufactured more economically when the slots are grouped in pairs in this way.

40 In addition slots produced in my manner have the following special characteristic. As is noted from Figs. 3, 5 and 8, the walls of each slot are parallel with each other for a substantial distance starting at the inside surface of the pipe and passing outward 45 through the slot toward the outside surface of the pipe. Toward the outside of the pipe, however, the slot walls furthest from each other in any pair of slots, are quite sharply inclined toward each other so as to give the 50 slot a pronounced taper immediately under

the outside of the pipe where the influence of the pressure roll was felt. Such slots having all their taper concentrated near the outside of the pipe, instead of a slow, gradual taper from the same slot width at the outside of the pipe to the same slot width at the inside, have a certain screening advantage as follows: In the usual slots which have only a slow, gradual taper, a sand particle may squeeze through the mouth of the 55 slot, and immediately thereafter, say one quarter way through the slot, may roll on its axis and become bound or jammed between the slot walls, thereby creating a nucleus against which smaller particles of sand 60 can subsequently lodge to gradually clog the slot. However, if the taper of the slot is pronounced as in my case, instead of only 65 gradual, the likelihood of such a particle jamming and sticking in the slot is considerably reduced, and therefore a screen 70 equipped with slots of my character is still less apt to clog than screens having only the slow gradual taper in the slots.

I claim:

75 Screen pipe having pairs of straight elongated slots formed integrally in the metal of the pipe and extending in a direction substantially parallel to the axis of said pipe, the slots in each pair being close together 80 compared with the distance between pairs and having a bar between the slots in the pair, the slot walls furthest from each other in any pair being parallel with regard to each other toward the inside of the pipe and inclined toward each other toward the outside of the pipe, and the slot walls nearest to each other in any pair being parallel 85 to each other throughout the thickness of the pipe so as to make the slots of uniform width toward the inside of the pipe but with pronounced taper toward the outside in order to make the slots narrower toward the 90 outside surface of the pipe than at the inside surface.

95 Signed at Los Angeles in the county of Los Angeles and State of California this 16th day of June, 1925.

ROBERT ALEXANDER STEPS.
